ratories Incorporated, Chicago, Ill., a corpora-
tion of Illinois

Application July 7, 1930, Serial No. 466,002

8 Claims. (Cl. 237—2)

This invention relates to a new and improved heating system of the internal combustion boiler type in which a heating medium consisting of mixed steam and products of combustion is created and transmitted to and through the radiators.

According to this invention the entire system is operated under a reduced pressure produced by a fan or other suction means connected with the outlets of the radiators. This exhausting mechanism draws out from the radiating system and expels to the outer atmosphere the non-condensable gases after they have given up most of their heat in the radiators, and also maintains a sub-atmospheric pressure in both the radiating system and the generator. Steam condensed in the radiating system is returned by gravity to the generator for reconversion into steam. The sub-atmospheric pressure maintained in the generator serves to draw in air from the outer atmosphere for combustion purposes, this sub-atmospheric pressure being reduced to provide for an increased supply of combustion air, when the number of radiators in service and hence the volume of the condensing space and the corresponding rate of condensation is increased. The entire system within the building to be heated is closed, and since the system is operated under reduced pressure, if any leakage does occur, it will be of air into the system rather than the escape of steam or combustion gases therefrom. Means manually operable from a location in the building remote from the generator is provided for starting and adjusting the generator burners, and for starting and stopping the exhausting mechanism. Signal devices adjacent the manually operable control means indicate the condition at any time of the generator and exhausting apparatus. Thermostatic control means automatically adjusts the fires in the generator in accordance with temperature requirements.

The principal object of this invention is to provide an improved heating system of the type briefly described hereinabove and disclosed more in detail in the specifications which follow.

Another object is to provide a simplified heating apparatus of the internal combustion boiler type operating under sub-atmospheric pressures.

Another object is to provide an apparatus of this type designed to prevent leakage of gases into the building.

Another object is to provide improved remote control means for stopping, starting and adjusting the various features of the apparatus.

Another object is to provide improved signal

means for indicating the condition of adjustment of the operating parts.

Another object is to provide improved thermostatically controlled means for adjusting the generator fires in accordance with temperature changes at a remote location.

Another object is to provide an improved type of generator for a mixed fluid heating medium.

Another object is to provide a simple, inexpensive and efficient heating system for small structures, which will give a maximum of convenience and comfort at a minimum of care and expense.

Other objects and advantages of this system will be more apparent from the following detailed description of one approved form of apparatus adapted for carrying out the principles of this invention.

In the accompanying drawings:

Fig. 1 is a general diagrammatic elevation of 20 the heating system.

Fig. 2 is a central vertical section through the generator.

Fig. 3 is a plan view of the generator, partially in horizontal section.

Fig. 4 is a detail plan view, partially in section, showing the ignition apparatus and pilot burners.

Fig. 5 is an elevation, partially in vertical section, through one of the thermostatic control devices.

Fig. 6 is a vertical section, taken substantially on the line 6—6 of Fig. 7, showing the electrically operated valve and switch mechanism.

Fig. 7 is a vertical section, taken substantially on the line 7—7 of Fig. 6.

Fig. 8 is a detail vertical section, taken substantially on the line 8—8 of Fig. 7.

Fig. 9 is a diagrammatic assembly showing a wiring diagram and the fuel-feed connections, and a vertical section through the temperature controlled valve.

Fig. 10 is a partial elevation and partial vertical section showing one of the radiator inlet valves.

The main elements of the apparatus are a generator A for the heating medium, a burner control mechanism indicated generally at B, a manually operated remote control and signal mechanism indicated at C, a thermostatically operated temperature control mechanism indicated at D or D', a radiating system comprising the several radiators E, and an exhausting mechanism indicated at F.

The generator A may take a variety of forms, a preferred form of generator being disclosed by

way of example in the present application. The generator herein disclosed is claimed in our co-pending application Serial No. 759,966, filed December 31, 1934.

5 One of the essential characteristics of this generator is that it is entirely closed except for the inlets for water, fuel and combustion air, and the outlet for the heating medium and excess water, none of these having any direct communication with the atmosphere within the building so that a reduced pressure may be maintained within the generator and the escape of fluids therefrom is prevented. The generator may be 10 made of metal or suitable refractory materials, or both, preferably comprising an outer metallic shell covered with suitable insulating material (not here shown) in order to prevent heat losses. In the example here shown, a lower substantially closed metallic housing 1 rests upon 15 and is sealed to a concrete supporting base 2 formed with the sump 3, from which leads drain pipe 4 provided with the downwardly looped water seal 5. Drain pipe 4 may empty into the sewer connection indicated at 6. A side extension 7 of the lower casing 1 houses the burner and control valve mechanism, and a conduit 8 for the combustion air leads in at 9 from the outer air and connects with the housing extension 7, from which this air flows through and 20 around the burner 17 into the main housing 1 and thence with the fuel into the combustion chamber. If permitted by local ordinances, the air inlet 8 may take in air from within the building without substantially affecting the operation 25 as hereinafter set forth. Suitably mounted in and supported by the metallic cover plate 10 of lower casing 1 is the main lower combustion chamber 11 formed of suitable refractory material. The refractory shell 11 for the combustion 30 chamber may be supported in a metallic casing 12 formed with a lower inwardly extending supporting flange 13 and supported from cover plate 10 by the angle brackets 14. The central cylindrical combustion chamber 15 is open at its 35 upper end and provided adjacent its lower end with a tangential inlet opening 16, through which the fuel and flame from main burner 17, and the combustion air, enter the combustion chamber 15. Due to this tangential opening, the combustion 40 fluids and flame take a spiral or spinning path through the combustion chamber 15, whereby a very long flame and complete combustion may be attained almost entirely within the relatively small combustion chamber before the hot 45 products of combustion pass out into the mixing chamber thereabove.

The outer substantially cylindrical metallic shell 18 of the steam generator and mixing chamber is supported by and secured to the cover plate 10 of lower casing 1 by means of annular bracket 19. The dome or cover 20 of casing 18 leads up to a central opening, with which communicates the outlet or main supply pipe 21, through which the heating medium is conducted to the radiating system. An inner metallic shell 22 is provided at its lower end with an outwardly extending flange 23 which joins with the outer shell 18, and is formed at its top with a dome 24 provided with a central opening through the downwardly extending cylindrical overflow flange 25. This overflow opening 26 is in line with the outlet pipe 21 and also serves as an outlet for the heating medium from the mixing chamber 27 within inner casing 22. A shallow flash plate or pan 28 is supported by legs 29 from cover plate 10, the flash

plate 28 being positioned substantially centrally within the mixing chamber 27. A water-heating pan 30 is supported beneath overflow opening 26 by post 31 extending upwardly from the flash plate 28.

5 A water supply pipe 32 communicates with the annular water space 33 between casings 18 and 22. This pipe 32 leads from the lower portion of return pipe 34 through which condensate is returned to the generator. A supply pipe 35 leading from the outside water supply and provided with cut-off valve 36 also communicates with the water inlet pipe 32. A scale-collecting pocket 37 may be provided at the lower end of the water return pipe 34.

10 The space between cylindrical casings 18 and 22 will be filled with water up to the level of the upper edge of overflow opening 26. 38 is a drain plug whereby this annular chamber 33 may be drained and flushed out, and 39 is a pet-cock to 20 test the upper water level. As additional water slowly accumulates in this annular space 33, due to the return of condensate from the heating system, the water will overflow through opening 26 into the heating pan 30, as indicated by the falling drops 40. Excess water in heating pan 30 will overflow, as indicated by the drops 41 onto the flash plate 28. The water which fills the annular space 33 and the pan 30 when the operation of the generator is first started will expand 30 when heated so as to start the overflow into pan 30 and onto flash plate 28.

15 In operation, the highly heated products of combustion rising from combustion chamber 15 pass under and around the flash plate 28 so as 35 to convert all or the greater portion of the film of water thereon into steam. These products of combustion also contact with the water falling through or from overflow opening 26 and from heating pan 30, whereby additional steam is generated. The rising products of combustion 40 highly heat the pan 30 and the water contained therein so that some steam will be generated from this body of water and the water which drops onto the flash pan 28 will already be raised to a high 45 temperature. The hot gases rising through mixing chamber 27 will soon heat the annular body of water in chamber 33 so that additional steam is generated from this water, all of the mixed gases consisting of steam and products of combustion passing out through the main supply pipe 21 to the radiating system. It will be noted that the mixing chamber 27 is entirely closed at its lower end by plate 10, the only inlet being through the relatively small inlet opening 16 provided for 50 the flame and combustion air, and the only outlet being through the supply main 21 for conducting out the heating medium. The entire generator will be protected by an outer covering of insulating material (not here shown), so that the heat 60 losses will be minimized, and practically all of the heat generated is carried out to the radiating system by the heating medium discharged through pipe 21.

55 Since practically all of the condensate from the radiating system is returned to the generator through pipe 32, and since additional water is always being formed in the combustion process from the hydrogen in the gas and oxygen in the air, there will ordinarily be a surplus of water 70 supplied to the generator. Any excess water that is not vaporized on flash pan 28 will overflow, as indicated at 42, onto the plate 10 forming the bottom of the mixing chamber 27, and then drain out through pipe 43, water seal 5, and drain pipe 4 75

to the sewer connection 6. The water seal 5 prevents the inflow of air at atmospheric pressure through pipe 43, or the escape of combustion gases through pipe 43 from the mixing chamber.

5 The heating medium passes from supply main 21 through the respective risers 44 and inlet valves 45 into the several radiators E. While only three radiators have here been shown by way of example, it is to be understood that a greater 10 number of radiators could be used. Each inlet valve 45 comprises the usual cut-off valve operated by handle 46, and a metering plate 41 provided with a central orifice 48 is interposed between the valve chamber and the passage 49 leading into the radiator E. The orifice 48 in plate 41 will be proportioned to meter the right proportion of heating medium to each radiator, depending upon the size, volume and condensing capacity of the radiator. It will be understood 20 that when valve 45 is closed practically no heating medium at all is admitted to the radiator, but when the valve is opened, a restricted flow of heating medium is admitted to the radiator through the orifice plate 47.

25 Discharge pipes 50 lead from the respective radiators E into the vertical return main 34, in the lower portion of which the condensate from the radiators accumulates and flows back through pipe 32 into the generator. At a point somewhat 30 above the water level in the generator A, a branch pipe 51 leads from return main 34 to the exhausting apparatus F. This exhausting apparatus 35 comprises a suitable fan or other suction device 52, driven by electric motor 53 and adapted to draw gases from return main 34 through pipe 51 and discharge these gases through pipe 54 into the outlet flue or chimney, indicated in dotted lines at 54'. This exhausting apparatus F, not 40 only draws out and expels the non-condensable gases from the radiating system but serves to create a small suction or sub-atmospheric pressure in the system which is increased by the vacuum created by condensation of steam in the radiators E. This sub-atmospheric pressure, 45 which extends into the generator A, serves to draw in the combustion air at atmospheric pressure and also prevents leakage of combustion gases from any part of the system since leakage (if any occurs) will be of air into the system, due to the 50 sub-atmospheric pressure existing therein.

The manually operated control mechanism B and C, whereby the heat is turned on and off from a point remote from the generating apparatus, for example from some room in the house that is being heated, will now be described, referring more particularly to Figs. 6, 7 and 8, and the diagrammatic showing in Fig. 9. The fuel gas flows into the valve casing 55 through pipe 56 from the source of supply, such as the city gas mains. 60 The cylindrical hollow sleeve valve 57 is rotatably journaled in valve casing 55, this sleeve valve being closed at one end 58, and open at the other end 59, to communicate through pipe union 60 with the thermostatically controlled regulating valve 61. Sleeve valve 57 is formed with an inlet port 62 which, in one position of the valve, communicates with a similarly shaped port 63 in the valve casing communicating with the main supply chamber 64. An arcuate extension 65 of supply chamber 64 extends around one side of the rotatable sleeve valve, and a smaller inlet port 66 leading from extension 65 is adapted to communicate with the inlet port 62 in the sleeve valve when this valve has been rotated through 75 an arc of 90 degrees from the position shown in

Fig. 8. The sleeve valve 57 is adapted to be rotated in one direction through successive arcuate steps of 90 degrees each, by means hereinafter disclosed. In one position, as shown in Figs. 7 and 8, the ports 62 and 63 will be in communication and a maximum flow of fuel gas through the valve will be permitted. At the next following position of the valve, the ports 62 and 66 will be in communication and a restricted flow of gas through the valve is permitted. This restricted 10 flow may be regulated by means of the adjusting screw 67, which is adapted to vary the effective size of port 66. In the next two successive positions of sleeve valve 57, reached by arcuate steps of 90 degrees each, the flow of gas through the 15 valve will be entirely cut off.

From the closed end 58 of sleeve valve 57, a cylindrical metallic shaft or spindle 68 projects into the contact box 69 provided on its opposite face with a removable closure plate 70. A disc 71, the hub of which is secured to spindle 68 by any suitable means, such as pin 72, is provided on one face with four similar pins 73 spaced at equi-distant points around the periphery of the disc. A lever 74 fulcrumed intermediately at 75 25 has its lower arm 76 pivotally connected with the outer end of the core or armature 77 of a solenoid or electro-magnet 78. A pawl 79 having one hooked end 80 adapted to engage any one of the several pins 73, is pivotally mounted at its 30 other end 81 on the free upper end of arm 82 of intermediately pivoted lever 74. A coiled contractile spring 83 is anchored at one end 84 in housing 69, and is secured at its other end to a lug 85 projecting upwardly from pawl 79 near its 35 pivoted end 81. This spring 83 tends to return the parts to the position shown in Fig. 6 when magnet 78 is de-energized, and also tends to swing the hooked end of pawl 79 downwardly so as to always be in position to engage one of the pins 40 73.

Referring now for a moment to Fig. 9, the line wires 86 and 87 supply current to a transformer indicated diagrammatically at 88, from which lower voltage current is supplied to certain elements of the control and signal mechanism. Current flows from transformer 88 through wires 89, 90 and 91 to the normally open push button 92 of the manual control mechanism C (see Fig. 1), then through wire 93 to the electro-magnet 78 and 50 wire 94 back to the transformer. Whenever push button 92 is closed, the magnet or solenoid 78 will be energized, thus drawing in core 77 and through lever 74 moving pawl 79 toward the right (Fig. 6), thereby turning the rotary assembly consisting 55 of sleeve valve 57 and spindle 68 and the parts mounted thereon, through an angle of 90 degrees. When the push button 92 is released, the magnet 78 will be de-energized and spring 83 will return the parts to the position shown in Fig. 6, the bevelled end 85 of pawl 79 sliding up over the next succeeding pin 73 until the hooked end 80 of the pawl can be moved down into engagement with this pin through the effort of spring 83 exerted on lug 85 of the pivoted pawl. The next time 60 push button 92 is closed, the same cycle of events will be repeated and the rotary assembly will be shifted in the same direction through another arc of 90 degrees.

A pair of signal lights which may conveniently 70 comprise a lower red light 96 and an upper white light 97, are preferably mounted adjacent the push button 92 as a part of the control mechanism C, as indicated in Fig. 1. A contact bar 98 is constantly in engagement with spindle 68, this 75

contact 98 being connected through wire 99 with one terminal of transformer 88. A pair of contact pins 100 and 101 mounted in spindle 68 and spaced 180 degrees apart are adapted to alternately contact with the spring contact member 102, which is connected through wire 103 with one terminal of light 97. A similar pair of contact pins 104 and 105, spaced 90 degrees apart, are adapted to contact with spring contact member 106 which is connected through wire 107 with one terminal of the red signal light 96. The other terminals of the signal lights 96 and 97 are connected by the respective branch wires 108 and 109 with the wire 89 leading back to transformer 88.

A coiled leaf spring 110 is anchored at its inner end 111 in the housing 69, and carries at its outer end a pendulum 112. A normally open contact member 113 is mounted at an intermediate point on the coiled spring 110, said contact 113 being adapted to intermittently engage with a relatively fixed contact member 114 carried by arm 115 as the spring vibrates, due to the oscillatory movement of pendulum 112. A finger 116 is anchored 25 on the spindle 68 in such a position that when the rotary assembly is moved through one arcuate step of 90 degrees, this finger 116 will snap past the pendulum 112, thus throwing this pendulum into oscillation and intermittently making and 30 breaking the contacts 113, 114. The primary winding of a spark coil 117 is energized from transformer 88 through a circuit comprising wire 89, wire 118, spring 110, contact 113, contact 114, wire 119, primary of coil 117 and wire 120 back to 35 transformer 88. The spark-plug 122 is connected in series with the secondary of spark coil 117 through wires 121 and 121'. It will now be apparent that whenever the pendulum 112 is set in motion, the contacts 113, 114 will be intermittently 40 brought into engagement so as to give a series of sparks at the spark plug 122.

A disc 123 of insulating material is fixedly mounted on spindle 68, this disc having one flat side 124. A movable contact member 125 will be held in engagement with a relatively fixed contact member 126 as long as the spring arm 127 which carries the contact 125 is held up by the cylindrical periphery 128 of insulating disc 123, on which it rests. Whenever the 45 flat face 124 of the disc comes under the arm 127, this spring arm will be permitted to move downwardly, thereby breaking the circuit by disengaging the contacts 125 and 126. One of these contacts 125 is connected with main 50 87 through wire 129. The other contact 126 is connected through wire 130 with one terminal of the exhaust motor 53. The other terminal of this motor is connected through wire 131 with the main 86. It will now be apparent that as 55 long as the contacts 125 and 126 are held together, the exhaust motor 53 will operate, but when the contacts 125 and 126 are separated, the motor 53 will be de-energized and the exhaust fan will stop.

The rotary assembly comprising sleeve valve 57 and spindle 68 and the contacts carried thereby, rotates intermittently in a clockwise direction, as seen in Figs. 6 and 8. In the first or "off" position, with all parts at rest or not functioning, this rotary assembly will be turned back in a counter-clockwise direction 90 degrees from the position shown in Figs. 6 and 8. At this time the valve 57 will be closed and no gas will flow 60 to the burners since closed portions of the sleeve

valve 57 will be over the inlet ports 63 and 66. At this time the spring arm 127 will be resting on the flat side 124 of insulating disc 123 and contacts 125 and 126 will be separated so that exhaust motor 53 is de-energized. At this time 5 none of the contact fingers 100, 101, 104 or 105 will be in engagement with the spring contacts 102 and 106 and neither of the signal lights 96 or 97 will be energized. The finger 116 will be back 90 degrees in a counterclockwise direction from 10 the position shown in Fig. 6, thus being behind the pendulum 112 and in position to impart an oscillatory movement to this pendulum when swung to the Fig. 6 position.

With the parts in the positions just described, 15 if push button 92 is closed, the solenoid 78 will be energized acting through the lever and pawl mechanism already described to swing the rotary assembly through an arc of 90 degrees to the positions shown in Figs. 6, 7 and 8. The valve will 20 be moved to the fully open position shown in Fig. 8 so as to supply a maximum flow of gas to the burners. The finger 116 will snap past the pendulum 112, thereby causing the spark plug 122 to give a series of sparks and ignite the pilot lights, 25 hereinafter described. The cylindrical surface 128 of disc 123 will be moved under spring arm 127, thereby closing the contacts 125, 126 and causing the exhausting mechanism F to operate. The two contact fingers 100 and 104 will be 30 moved into engagement with the spring contact arms 102, 106, thereby causing both signal lamps 96 and 97 to be lighted. The two lights 96 and 97 burning simultaneously indicate that the main burner 17 is being supplied with a maximum flow 35 of gas.

If it is desired to restrict the flow of gas to the burner 17 and thus cut down the heat output, contact button 92 will be closed a second time, thereby moving the rotary parts through 40 a second arc of 90 degrees. This will bring the port 62 in sleeve valve 57 in line with the restricted inlet port 66, whereby only a reduced flow of gas to the burner is permitted. The contact fingers 100 and 104 will be moved out of engagement with spring contacts 102 and 106, but the contact finger 105 will be moved into engagement 45 with spring contact 106 so as to continue the illumination of the lower red light 96, thus indicating that the low or reduced heat is on. The 50 upper white light 97 will not be illuminated at this time. The exhaust will continue to function since the cylindrical surface 128 of disc 123 is still in contact with spring arm 127.

A third operation of push button 92 will completely close the valve so as to cut off all flow of 55 gas to the burners (both main and pilot burners). However, the exhaust will continue in operation since the cylindrical surface 128 of disc 123 is still beneath the spring arm 127. Even though 60 the fires have been shut off, the exhaust will continue to draw the unused heating medium already generated into the radiators where the heat will be given off where needed, instead of being wasted in the generator. At this time the contact pin 101 will be moved into engagement with spring contact 102 so as to illuminate the white light 97, the red light 96 being de-energized since 65 both contact pins 104 and 105 will be out of engagement with spring arm 106. A fourth operation of the push button 92 will complete the cycle 70 and return all of the parts to the position first described, with both lights out, the valve completely closed and the spring arm 127 resting on 75

flat side 124 of disc 123, so that the exhauster fan will cease to operate.

The gas flows from valve casing 55 through union 60 into the valve casing 61, already referred to, which contains a web 132 separating the inlet chamber 133 from the outlet chamber 134. When the passage 135 in web 132 is open, the gas will flow from chamber 133 into chamber 134 and thence through pipe connection 136 to the main burner 17. A small pipe 137 leads from the inlet valve chamber 133 to the nozzle 138 of the pilot burners which nozzle is positioned in the upper end of a chimney 139. A relatively small pilot flame 140 projects through the open upper end of chimney 139 and is adapted to be ignited by the spark plug 122, already described. This flame 140 in turn ignites a larger pilot flame 141 which projects through an opening 142 in the side of the chimney into position to ignite the main burner 17. It will be noted that these pilot lights will burn at any time that gas is allowed to flow through the electrically operated valve 55 into the temperature control valve 61.

A small gas pipe 142 is connected by fitting 143 into the inlet chamber 133 of valve 61, the pipe 142 extending into the closed chamber 144 of thermostatic temperature control device D, a pipe 145 leading from this chamber 144 to a pilot burner 146 positioned in the lower end of chimney 139, already referred to. The pipe 145 extends into chamber 144 and terminates in an open flared end 147 adjacent a flexible diaphragm 148 which forms one wall of chamber 144. A plunger 149 is adapted to depress the diaphragm 148 and thus close the opening 147 to discharge pipe 145, the plunger being operated by a thermostatic bar 150 which may be set to operate at certain designated temperatures by means of the adjusting device indicated at 151. Normally, whenever a flow of gas is permitted to pass to control valve 61 through the electrically operated valve 55, gas will flow through pipe 142 to chamber 144 and thence through outlet pipe 145 to the pilot burner 146. The gas from this burner will flow up the chimney 139 and be ignited by the previously ignited pilot flames 140 and 141 at the upper end of the chimney, this pilot burner 146 then flashing down to the normal position indicated in Fig. 9. Pilot 146 will burn continuously until a predetermined temperature is reached at the location of thermostatic control device D, whereupon the diaphragm 148 will be depressed to close the outlet 147, thus cutting off the supply of gas to pilot burner 146. A thermostatic bar 152 is positioned in chimney 139 above the pilot burner 146, and when heated by this burner, this bar 152 will bend toward the left, Fig. 9, and operate through rod 153 to push over to the left the lever 154, which is connected through rod 155 with the main valve 156 for closing port 135 in web 132. A spring 157 serves to snap the valve to its fully open position when lever 154 has been moved past a mid-point. Valve 156 is mounted for universal adjustment on a ball 158 at the end of operating rod 155, and spring 159 serves to seat the valve over port 135.

Before operations are commenced, thermostatic bar 152 will be cold and main valve 156 will be closed, the parts being in the position shown in Fig. 9. As soon as the electrically operated valve 55 is opened and gas flows to chamber 133, gas will immediately flow from this chamber to the several pilot burners already described, the pilot flame 140 being ignited from spark plug 122 and subsequently serving to light the main pilot flame

141 and the control pilot flame 146, in the manners already described. The flame 146 will heat up bar 152, which will move to the left, causing main valve 156 to be opened, thus permitting gas to flow to the main burner 17 the flame of which will be ignited from the main pilot flame 141. All of these burners will continue to operate until the maximum temperature for which adjusting means 151 is set is reached at the location of control device D or D', whereupon this device will operate to cut off the flow of gas through pipe 145 to the pilot burner 146. The thermostatic bar 152 will now cool off and move toward the right, whereupon the main valve 156 will be closed to cut off flow of gas to main burner 17. The pilot flames 140 and 141 will continue to burn. When the temperature adjacent control device D has fallen sufficiently, the diaphragm 148 will move away from opening 147, thus permitting gas to again flow to the pilot burner 146, the flame of which will again be ignited from the pilot flames 140 and 141, again heating bar 152 so that main valve 156 will be opened and main burner 17 will again be ignited from the pilot flame 141. This cycle of operations will repeat itself as temperature conditions demand. If the temperature should for any reason rise too high, the main burner 17 will be cut off in the manner already described, until the temperature has been lowered below the desired maximum. In actual operation, the main valve 156 will stabilize itself in an almost fully open position, such that the heat delivered from burner 146 is just sufficient to keep the various elements of the valve system in equilibrium.

In the example shown in Fig. 9, the temperature control device D has been positioned in or adjacent the outlet port 51 for the exhaust gases, so that when these gases come out too hot, thus indicating that more heat is being furnished to the radiating system than is demanded thereby, this device D will operate to cut off the burners. The control device D' (which may be connected in series in pipe line 142 with the similar device D) could be positioned in any room of the building that is to be heated, and adjusted to be responsive to the desired temperature in that room. Several of these control devices D' could be connected in series so that the gas flow to pilot burner 146 must pass through all of these devices. In such an installation, if a maximum temperature is exceeded at the location of any one of these devices D or D', the supply of gas to pilot 146 will be cut off.

To summarize the operation, after a period of disuse and assuming that the generator is properly supplied with water, it is merely necessary for the occupant of the building to press the control button 92 in order to start the system. Gas will immediately be supplied to the pilot burners and they will be automatically ignited, and the main burner 17 will be put into operation after main valve 156 has been opened by the operation of pilot burner 146. The exhauster will be put into operation so as to lower the pressure in the system, drawing combustion air into the generator and causing the heating medium to flow into the radiating system. The cooled non-condensable gases will be expelled from the building through outlet pipe 54 and flue 54', and the condensate and water generated by the combustion process will be returned to the generator. The automatic temperature control devices D or D' will function to cut down or turn off the main burner when desired maximum tem-

perature has been reached either in the gases that are being withdrawn from the system, or in such of the spaces being heated as have their temperatures controlled by the thermostats D' positioned in these spaces. In mild weather when less heat is demanded from the system, the control button 92 can be pressed a second time so as to manually cut down the maximum flow of gas to the system. By pressing the control button 92 a third time the functioning of the generator may be entirely discontinued by cutting off all of the burners, but the exhauster will continue to operate so as to keep up a flow of the generated heating medium through the radiating system, thus keeping the radiators warm as long as any of this heating medium remains. A fourth operation of button 92 serves to cut off the exhauster and entirely stop the operation of the system. It will be noted that when the exhauster is out of operation there is no flow of gas to any of the burners, including all pilot burners, so there is no danger of unburned gas or products of combustion escaping into the building. At all times when the burners, or any of them are in operation, the exhauster is operating to reduce the pressure in the system so that if any leakage occurs it will be of air into the system rather than of gases out of the system into the building.

30 By having one or more of the inlet valves 45 drilled so that they can never be fully closed (at locations where heat will usually be required, if at all), a diminished flow of fluid through such radiator or radiators will be permitted even though all of the inlet valves 45 are closed. Since such radiator or radiators will probably be unable to utilize all of the heat developed, the hot gases will be drawn out through pipe 51, causing control device D to operate to shut off the main burner in the manner already described.

35 It will be noted that all of the main valves, burners, and operating parts therefor are carried by the removable door plate 160 forming one wall of casing extension 7, whereby all of these parts will be readily accessible for testing, replacing, repairing, etc.

40 Emergency pressure relief valves and observation ports may be installed in each of the supply and return sides of the system. In Fig. 2 the casing 161 has a lower flange 162 for holding to the top 20 of the generator, and is internally threaded in its upper end 163 to receive the supply main 21. The casing 161 is formed internally so that water will drip and run downward out of the casing. The flap or closure 164 is hinged at its upper edge 165 and rests upon the inclined seat 166 so that it will be held shut by gravity, also by the outer atmospheric pressure when the system is normally operating under a partial vacuum. The flap 164 is thick enough not to warp under the temperatures to which it is subjected, and may if desired, be made of brass or other non-corrosive metal to prevent rusting shut. If, for any reason, super-atmospheric pressures should be developed in the system, this flap valve will blow open and relieve the pressure. The flap 164 may also be raised manually for observation purposes.

45 A similar flap-valve 167 is positioned in the return main, for example, above the connection with pipe 51, as shown in Fig. 1. This relief and observation valve 167 is the same as the valve 161, except that an interiorly threaded pipe-receiving lower end similar to the upper end 163, is substituted for the attaching flange 162.

These heating units are designed for heating small or medium sized homes, but in case of a larger structure where one of these units is insufficient, two or more units may be combined for simultaneous operation. A removable end plate 168 is provided at the outer end of housing extension 7, whereby two of these housings may be connected together and both supplied with air from a single inlet pipe 8. The return main 34 may be provided with two branch pipes 32, whereby condensate will be distributed between two generators A, and a single exhausting mechanism F can withdraw and expel the gases from both systems if desired. The same control devices, both manual and automatic may be connected up to simultaneously control both generators, or the control devices may be kept separate, if separate zone control is desired. It will be obvious that this same principle can be applied to more than two units. In case two or more generating units are thus used, a larger exhausting fan F may be required, if only one is used.

50 It will be noted that these heating units are entirely self-contained and have no fluid outlet or inlet connections to permit escape of gas into any portion of the building being heated, and practically all portions of the generator and piping can be completely covered or insulated so as to reduce heat losses to a minimum. Practically the only heat losses will be in the gases expelled through the exhauster into the flue 54, and ordinarily these gases will give up most of their heat before being withdrawn from the radiators E. In case these discharge gases become too hot, the thermostatic device D will function to cut down the supply of heat to the generator.

55 The inside of all metal parts, such as the generator and the piping, that are subject to the corrosive action of the combustion gases may be provided with a vitreous coating or other form of rust proofing. This corrosive action is largely caused by excess air in the system. Since this improved system operates under a vacuum, excess air is practically eliminated and corrosion is minimized.

45 We claim:

1. A heating apparatus comprising a generator for a mixed fluid heating medium consisting of products of combustion and steam, said generator comprising a burner and a valve for controlling the supply of fuel to the burner, a radiating system comprising a plurality of separate radiators, an exhausting mechanism connected with all of the radiators for withdrawing gaseous products therefrom and creating a sub-atmospheric pressure therein and in the generator, conduits for the heating medium leading from the generator to the radiators, and thermostatic means for controlling the valve so as to decrease the fuel supply to the burner when the temperature of the gases exhausted from the radiating system exceeds a predetermined maximum.

2. A heating apparatus comprising a generator for a mixed fluid heating medium consisting of products of combustion and steam, a radiating system comprising a plurality of separate radiators, an exhausting mechanism connected with all of the radiators for withdrawing gaseous products therefrom and creating a sub-atmospheric pressure therein and in the generator, conduits for the heating medium leading from the generator to the radiators, and thermostatic means for decreasing the flow of fuel to the generator when the temperature of the

gases withdrawn from the radiating system exceeds a predetermined maximum, and for again increasing the flow of fuel when the temperature of the gases falls below this maximum.

5 3. A heating apparatus comprising a generator for a mixed fluid heating medium consisting of products of combustion and steam, a radiating system comprising a plurality of separate radiators, conduits for the heating medium leading from the generator to the radiators, an exhausting mechanism connected with the radiating system for withdrawing non-condensable gases therefrom and lowering the pressure therein and in the generator, manually operated means for remote control of the generator, and thermostatically controlled means for automatically decreasing the flow of the fuel to the generator when the temperature of the gases withdrawn from the radiating system exceeds to a predetermined maximum.

4. A heating apparatus comprising a generator for a mixed fluid heating medium consisting of products of combustion and steam, a radiating system comprising a plurality of separate radiators, conduits for the heating medium leading from the generator to the radiators, an exhausting mechanism connected with the radiating system for withdrawing non-condensable gases therefrom and lowering the pressure therein and in the generator, and manually operated means for simultaneous remote control of the generator and exhausting mechanism by successive actuations, one adjustment of said manually operating means functioning to cause the exhausting means to remain in action after the generator burners have ceased to function.

5. A heating apparatus comprising a generator for a mixed fluid heating medium consisting of products of combustion and steam, said generator comprising a burner and a fuel supply pipe leading thereto, a radiating system comprising a plurality of radiators, an exhausting mechanism connected with the radiators for withdrawing non-condensable gaseous products therefrom and creating a sub-atmospheric pressure therein and in the generator, conduits for the heating medium leading from the generator to the radiators, means for returning condensate from the radiators to the generator, a valve in the fuel supply pipe and thermostatically controlled means for automatically opening or closing the valve as the temperature of the gases exhausted from the system fall below or rise above respectively a predetermined temperature.

55 6. A heating apparatus comprising a generator for a mixed fluid heating medium consisting of products of combustion and steam, said generator comprising a burner and a fuel supply pipe leading thereto, a radiating system comprising a plurality of radiators, an exhausting mechanism connected with the radiators for withdrawing non-condensable gaseous products

therefrom and creating a sub-atmospheric pressure therein and in the generator, conduits for the heating medium leading from the generator to the radiators, means for returning condensate from the radiators to the generator, a valve in the fuel supply pipe, and thermostatically controlled means for automatically opening or closing the valve in response to variations below or above a predetermined temperature respectively in a space heated by the apparatus or when the temperature of the gases exhausted from the system respectively fall below or rise above a predetermined temperature.

7. A heating apparatus comprising a generator for a mixed fluid heating medium consisting of products of combustion and steam, said generator comprising a burner and a fuel supply pipe leading thereto, a radiating system comprising a plurality of radiators, an exhausting mechanism connected with the radiators for withdrawing non-condensable gaseous products therefrom and creating a sub-atmospheric pressure therein and in the generator, conduits for the heating medium leading from the generator to the radiators, means for returning condensate from the radiators to the generator, a pair of valves in the supply pipe, the flow of fuel to the burner being cut off when either valve is closed, manually operable means for remote control of the first valve and the exhausting mechanism, and thermostatically controlled means for automatically opening or closing the second valve as the temperature of the gases exhausted from the system respectively fall below or rise above a predetermined temperature.

8. A heating apparatus comprising a generator for a mixed fluid heating medium consisting of products of combustion and steam, said generator comprising a burner and a fuel supply pipe leading thereto, a radiating system comprising a plurality of radiators, an exhausting mechanism connected with the radiators for withdrawing non-condensable gaseous products therefrom and creating a sub-atmospheric pressure therein and in the generator, conduits for the heating medium leading from the generator to the radiators, means for returning condensate from the radiators to the generator, a pair of valves in the supply pipe, the flow of fuel to the burner being cut off when either valve is closed, manually operable means for remote control of the first valve and the exhausting mechanism, and thermostatically controlled means for automatically opening or closing the second valve in response to variations below or above a predetermined temperature in a space heated by the apparatus, or when the temperature of the gases exhausted from the system fall respectively below or rise above a certain predetermined temperature.
